UNITED STATES PATENT OFFICE.

JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA.

CORE GUIDE.

Application filed May 24, 1926, Serial No. 111,218. Renewed October 17, 1928.

This invention relates to core guides for positioning elongated cores in molds for casting pipe or other tubular castings by the horizontal method.

5 An object is to provide means on the drag section of a flask, may be put in exact longitudinal and lateral position relative to the mold, so as to insure a casting having walls with no thin places, which would be areas of 10 weakness in high pressure work.

Another object is to provide simple, strong and durable means which may be readily formed integrally with the said drag section, and made true and accurate by machining the 15 same, so as to coact with the extended end portion of the core bar being lowered into position by travelling crane or otherwise, and to cause said core bar to be directed to the exact center of the mold, after which, by a simple 20 longitudinal shifting movement of the core bar the same is stopped, by the improved means, in the exact lengthwise position desired.

A further object is to provide guiding 25 means for core bars of this character which will permit the latter to be lowered into position therein, no matter what the rotary position of the bar about its own axis may be, thus greatly facilitating the operation which may 30 be watched and directed by a single operative, it being understood that the said guiding means is preferably located only at the bell end of the flask, and that the bell end of the core bar is especially constructed for such 35 co-action.

A full and complete understanding of the invention may be obtained from a consideration of the following detailed description, taken in connection with the accompanying 40 drawings forming a part of this specification, it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended claims.

In the drawings, in which similar reference characters designate corresponding parts throughout the several figures:—

Figure 1 is a plan view of a double pipe flask, partly broken away, the cores being held

in position therein and in coaction with the improved guiding means.

55 Figure 2 is an end elevation of the bell end of the flask, drawn on an enlarged scale and showing the core bars in section and in coaction with the guides.

Figure 3 is a horizontal sectional view 60 through the flask of Figure 2.

Figure 4 is a vertical sectional view through Figure 2, the core bar being shown in dotted lines.

Figure 5 is a detail perspective view showing the double guide located between the pair of core bars.

65 A modern flask such as is in general use for horizontal casting in a pipe foundry has been shown in the drawing, provided with the improved guide, said flask being of the double or twin form wherein two pipes may be formed at a single pouring of the molten metal; but it is to be understood that the invention may also be incorporated in a single pipe flask or 75 in one where three, four or more castings are made at one time.

80 Furthermore there have been illustrated in the drawing certain means for rigidly holding the core bars from sagging from their own weight or from being elevated or floated at their intermediate portions by the inflowing molten metal, but such means forms no part of the present invention and no claim is 85 made thereto in the present application, it having been included herein merely to show that the present improved guiding means may be used in connection therewith, as the same forms the subject matter of my patent on means for supporting core bars in flasks, 90 No. 1,601,450, which has been reissued as Re-issue No. 17,121.

95 As shown in the drawing, the flask comprises the usual drag section 1 and the coacting cope section 2 adapted to be inverted and placed thereover, after the usual sand molds have been formed therein. At each end the drag section is provided with a relatively heavy end wall 3, while the cope section is likewise provided with similar end walls 4, 100 each joining longitudinal side walls of the drag and cope respectively to form open, rectangular frames fitting each other, and adapted to permit the sand to be readily shaken out after casting. The drag section 105 is provided with a series of transverse, inte-

grally formed webs 5 to strengthen the structure, while the cope is also provided with similar webs 6 for the same purpose.

As has been stated, the guides are preferably located at the bell end of the flask, and no attempt has been made in the drawing to fully illustrate in detail the other or spigot end of the flask and cores. The end walls 3 and 4, however, at each end of the flask, are each provided with a semi-circular opening coacting, when placed together, to form a complete circular opening for the adjacent end of the core bar to project through, that opening in the drag section being indicated at 7 and the corresponding opening in the cope at 8. The diameter of the combined openings 7 and 8 is somewhat larger than the diameter of the core bar which extends centrally through the same, and the aforesaid transverse web 5 next adjacent to the bell end wall 3 of the drag is provided with a semi-circular opening or seat 9, which is of the same diameter as the core bar. There is a corresponding seat (not shown) at the other end of the drag, and each seat is preferably machined to fit the core bar and to coact with means to be described in a manner to rigidly clamp the bar and resist sagging due to the weight of the core bar or floating due to the molten iron.

The transverse web 6 of the cope section next adjacent to the end wall 4 thereof is also provided with a semi-circular opening 10 of greater diameter than the core bar 11 and does not touch the latter, and it will be understood that all the other intermediate, reinforcing webs arranged transversely of the cope and drag sections of the flask are provided with coacting, semi-circular openings of greater diameter than the core on the core bar.

As shown in Figure 1 of the drawings the core bars extend beyond the end walls of the flask sections, and it will be seen that the areas between the end walls and the next adjacent transverse webs are devoid of sand when the molds are made in the flask, said areas being utilized for the location of clamping and holding means as has been mentioned herein.

The bell ends of the illustrative core bars 11 are reduced adjacent to their terminals, and between the shoulders 12 thus formed and the ends of the bars, there is provided an outstanding, annular flange 13, preferably formed integrally therewith, and having a diameter greater than the core bar, all of said parts being carefully and accurately turned round, so that it does not matter what angular position the core bar may be in when lowered to be guided by the improved means to be described.

Beneath each core bar and in exact vertical line with the centers thereof, there is provided an outstanding lug 14 cast integrally

on the outer face of the end walls of the drag section, and at their outer ends said lugs are suitably apertured and threaded for the reception of set screws 15 adapted to bear upwardly against the under sides of the core bars during the operation of tensioning the latter. Longitudinal arms 16 located midway between the core bars, and beneath the same are integrally connected at their ends to the end walls 3 and the next adjacent transverse webs 5 of the drag sections, and said arms are provided with suitable sockets for the detachable reception of the heads of bolts 17, which extend vertically between the core bars, one at each end, and each bolt is adapted to draw a yoke 18 downwardly upon the tops of the core bars in opposition to the aforesaid machined seats 9 and the set screws 15 to hold the bars in a manner fully set forth in the aforesaid reissue.

At the bell end, the drag section 1 is provided with an integrally formed, central, outstanding lug 19, (Fig. 5), the same merging into the outer face of the end wall 3, as indicated at 20, and the upper end portion of said lug is reduced in width, longitudinally of the flask, thus providing a space 21 between the inner face of said lug and the outer face of the drag section, the upper end of the lug being located somewhat above the joint between the cope and drag sections, as clearly shown in Figure 4 of the drawings.

The central lug 19 is provided on its opposite side faces with inner, vertical ribs 22 which extend somewhat above and below the centers of the extended ends of the core bars, and the outer faces of said ribs are accurately machined to contact with the inner sides of the two core bars when the latter are in exact axial alignment with the molds in the flask. See Figs. 2 and 3. The upper ends of the ribs 22 are bevelled outwardly, as shown at 23, to provide flaring entrance openings and to deflect the bars to the proper position when the latter are being lowered. The ribs 22 engage the core bars adjacent to the aforesaid shoulders 12, as clearly shown in Figure 3. The central lugs 19 are furthermore provided with outer ribs 24, parallel to the ribs 22 and having their upper ends similarly bevelled at 25 for a similar purpose. The side faces of the outer ribs 24 are a greater distance from the centers of the core bars than the corresponding faces of the ribs 22, so as not to contact with the cylindrical walls of the core bars as do said ribs 22, see Fig. 3. The outer faces of the ribs 24, which are suitably machined, are adapted to contact with the inner annular faces of the flanges 13 of the core bars, and to act as stops when the core bars rest upon the seats 9, and are moved inwardly to bring the said flanges against said ribs 24.

Coacting with the central lugs are outer lugs 26 formed integrally with the drag section

and merging into the latter as at 27, the same being identical in form with the central lugs and spaced from the end wall 3 as at 21. These outer lugs, however, are provided only 5 on their inner faces with inner ribs 28 co-operating with the ribs 22 and bevelled at their tops (not shown), and with outer ribs 29 co-operating with the ribs 24 and bevelled as at 30 to facilitate the guiding of the core 10 bars into position.

It will be clear that if the flask is used for casting only one pipe length at a time, the central lug 19 with its guides will not be used, but two outer lugs 26 will be on opposite sides 15 of the single core bar. On the other hand, if more than two pipe lengths are cast in a single flask, there will be two or more lugs 19, one lug 19 being between each pair of adjacent core bars.

20 Any suitable form of lug or extension 31 may be formed on the drag section for lifting the same, or for lifting the entire flask, and the cope section may also be provided with suitable lifting lugs (not shown) for permitting 25 the two members to be separately lifted and reversed or otherwise handled to remove the sand therefrom, etc.

From the foregoing it will be seen that simple means have been provided for accurately 30 directing core bars or the like into proper position within a mold or in a seat, said means being readily formed integrally with the flask section and serving to permit careful inspection by a single operative while the core 35 bars or the like are being lowered by overhead power means, with the result that the cores are placed with absolute accuracy in the desired longitudinal and lateral position, without damage to the sand mold or the sand core, 40 and that it is immaterial what rotary position the cores may be in when lowered in the slings to be properly engaged and directed by the coacting ribs 22 and 28, the other ribs 24 and 29 serving to stop the flanges 13 with 45 the cores in exact longitudinal position within the molds.

What is claimed is:—

1. A flask for casting pipe or similar tubular objects horizontally, said flask being composed of a cope and a drag section, each having coacting openings to permit the core bar to extend therethrough, guides formed integrally with the drag section and extending above the center of the core bar and at each 50 side thereof, and means formed on the core bar for coaction with the guides to position the core bar both laterally and longitudinally.

2. In a flask for casting pipe or the like in a horizontal position, a cope and a drag section 60 each having coacting, semi-circular end openings, a core bar adapted to be supported in the flask and to extend at each end through said openings, upstanding lugs formed integrally on one end of the drag section and extending above the center of the core bar at

either side thereof where projecting through the flask, said lugs having their inner, opposed sides provided with machined faces where contacting with the core bar to laterally guide the same into position, and a machined, 70 annular flange formed on the core bar to contact with the outer faces of the lugs to longitudinally guide the core bar into position.

3. In a flask for the horizontal casting of pipe or the like, a cope and a drag section, a 75 core supported in the flask and having the ends of the bar thereof extended through the ends of said flask, lugs formed integrally on the outer face of the bell end wall of the said drag section and extending upwardly at either 80 side of the core bar, said lugs having spaced inner and outer, vertically disposed, machined ribs on their opposed faces, the inner ribs being adapted to contact with the core bar at either side to laterally position the core in the 85 mold within the flask, and a machined, annular flange formed near the end of the core bar and adapted to abut against the said outer ribs of the lugs to longitudinally position the 90 said core in said mold.

4. Means for guiding a core in a mold for horizontally casting pipe or the like, comprising a flask having a cope and a drag section, said sections having coacting openings at each end, a core supporting bar adapted to be supported in the flask with the ends thereof projecting through said openings, spaced lugs formed integrally on the outside of one wall 95 of the drag section and extending upwardly in spaced relation to said end wall, said lugs having spaced, vertically disposed, inner and outer ribs formed on their inner, opposed sides, the upper ends of the ribs being bevelled outwardly to provide tapered entrances 100 for facilitating the lowering of the core bar and core into the drag section of the flask, the opposed faces of the inner ribs being closer together than those of the outer ribs and adapted to contact with the opposite sides of the core bar in any rotary position of the latter and guide the same into accurate lateral 105 position in the mold, and an outstanding, circumferential flange formed on one end of the core bar and adapted to abut against the outer faces of the outer ribs to longitudinally position the core in the flask.

5. In a flask for casting pipe horizontally, a cope section and a drag section each provided with one or more complementary, semi-circular openings formed in the end walls 110 thereof, one or more core supporting bars adapted to be supported in the flask with the ends thereof projecting through said openings, guide lugs formed integrally on the outer face of the bell end wall of the 115 drag section, said lugs extending upwardly above the center line of said bar or bars, each lug having a vertical guide rib to contact with the side of the adjacent bar and position same laterally in the mold, each lug also 120

- having an outer vertical stop rib, and an outstanding, annular flange formed on the end of each core bar to abut against the outer face of the outer ribs to properly locate the 5 core bars lengthwise of the molds.
6. A flask for casting pipe and the like horizontally comprising, in combination, a cope; a drag; a core bar; means to clamp the core bar in the mold; and guiding means on the 10 drag so arranged as to contact with the core bar near one end thereof and serve as a stop to prevent inward longitudinal movement of the core bar such as would weaken or destroy the casting.
- 15 7. A flask for casting pipe and the like horizontally comprising, in combination, a cope; a drag; a core bar; the core bar extending beyond the ends of the flask; guides formed integrally with the drag at either 20 side of the core bar; and means formed on the core bar beyond or outside of the guides for coaction with the guides to properly position the core bar longitudinally.
- 25 8. A flask for casting pipe and the like horizontally comprising, in combination, a cope; a drag; a core bar; the drag having machined webs near its ends providing seats for the core bar; the core bar projecting beyond said seats; and co-operating means 30 provided on the drag and on the core bar for preventing such inward longitudinal movement of the core bar as would weaken or destroy the casting.
- 35 9. A flask for casting pipe and the like horizontally comprising, in combination, a cope; a drag; a core bar; the drag having machined webs near its ends providing seats for the core bars; said seats being semicircular to receive the core bar and make a nice 40 fit and prevent lateral movement thereof; the core bar projecting beyond said seats; and co-operating means provided on the drag and
- on the core bar for preventing such inward longitudinal movement of the core bar as would weaken or destroy the casting. 45
10. A flask for casting pipe or similar tubular objects horizontally, said flask being composed of a cope and a drag section, each having matching openings to permit the core bar to extend therethrough, guides formed 50 integrally with the drag section and at each side of the core bar, and means formed on the core bar for coaction with the guides to position the core bar both laterally and longitudinally. 55
11. Means for guiding a core in a mold for horizontally casting pipe or the like, comprising a flask having a cope and a drag section, said sections having matching openings at each end, a core supporting bar adapted to 60 be supported in the flask with the ends thereof projecting through said openings, spaced lugs formed integrally on the outside of one wall of the drag section and extending upwardly in spaced relation to said end wall, said lugs 65 having vertically disposed ribs, the upper ends of the ribs being bevelled outwardly to provide tapered entrances for facilitating the lowering of the core bar into the drag section of the flask, and an outstanding, circumferential flange formed on one end of the core bar and adapted to abut against the outer faces of the ribs to longitudinally position the core in the flask. 70
12. In combination, a flask section having 75 means for longitudinally guiding a core bar, said means consisting of a projection on one end wall of the flask section; and a projection on the core bar for contact with the outside of the projection on the flask section, 80 thus guiding the core bar.
- In testimony, that I claim the foregoing as my own, I have hereto affixed my signature.
- JAMES R. McWANE.
